UNITED STATES PATENT OFFICE.

CLARENCE W. NEUPERT, OF BUFFALO, NEW YORK.

PUMP.

Application filed December 8, 1921. Serial No. 520,950.

To all whom it may concern:

Be it known that I, CLARENCE W. NEUPERT, a citizen of the United States, residing in Buffalo, in the county of Erie and State of New York, have invented new and useful Improvements in Pumps, of which the following is a specification.

The object of this invention is the production of a pump which is more particularly designed for use in forcibly circulating the water in the engine cooling system of an automobile and to accomplish this by means which are simple in construction, efficient in operation and not likely to become clogged or get out of order.

In the accompanying drawings:

Figure 1 is a perspective view of my improved water circulating pump interposed between the radiator and engine of an automobile. Figure 2 is a vertical longitudinal section of the pump, on an enlarged scale. Figure 3 is a cross section taken on line 3—3, Fig. 2.

Similar characters of reference refer to like parts throughout the several views.

10 represents the water jacket of an automobile gas engine and 11 a radiator arranged in front of the engine and having its upper part provided with an inlet 12 which is connected by a tube 13 with the outlet 50 in the upper part of the engine water jacket.

My improved pump is interposed between the outlet 14 at the lower end of the radiator and the inlet 15 in the lower part of the water jacket and is constructed as follows:

16 represents the cylindrical wall or body of the impeller chamber 17 which is provided at its front end with an integral head 18 and at its rear end with a removable head 19 which is detachably connected therewith by screws 20. On its inner side the wall of the impeller chamber is provided with a liquid outlet 21 which extends laterally through a tubular neck 22 leading to the inlet of the engine water jacket and secured to the latter by screws 23. The removable head of the impeller chamber contains a liquid inlet 24 which communicates with the upper rear end of a water supply conduit 25, the lower front part extending lengthwise underneath the impeller chamber and being connected by a flexible tube or hose 26 with the outlet of the radiator.

Extending forwardly from the front head 25 is a tubular bracket 27 which is provided at

its front and rear ends with bearings 28, 29 and which is strengthened externally by longitudinal ribs 30. The front part of this tubular bracket is embraced by a collar 31 which is secured thereto by a set screw 32, the collar being provided on its inner side with a foot or brace 33 having a cam face 34 engaging with the adjacent part of the water jacket so that by turning this brace the pump casing may be held rigidly relatively to the engine.

49 represents the pump shaft which is arranged lengthwise in the tubular bracket and journaled in the bearings therein. The outer or front end of this shaft is provided with a driven pulley 35 which receives a driving belt 36 the latter also passing around the pulley 37 of the air fan 38 arranged in rear of the radiator and also around the driving pulley 39 arranged on the shaft of the gas engine in the usual manner.

Within the impeller chamber is arranged a rotary impeller whereby the water is drawn from the inlet at the rear end of the chamber into the latter and then expelled through its outlet in the side thereof. This impeller comprises a rotary disk 40 arranged adjacent to the front head of the impeller chamber and detachably connected with the pump shaft by an externally screw threaded shank 41 at the rear end of the pump shaft engaging with an internally threaded hub 42 on the impeller disk. The impeller also comprises a plurality of longitudinal impeller blades 43 which are arranged in an annular row and are connected at their front ends with the impeller disk while their rear ends are free and arranged close to and around the inlet 24.

By this means the water is able to pass freely from the inlet of the impeller chamber into the central part of the latter from which the same is discharged by the impeller blades through the outlet in the side of the chamber without liability of the chamber or impeller obstructing the path of the water and without danger of the same becoming clogged by foreign matter.

Owing to the water entering the impeller chamber centrally through its rear head the impeller blades which at its ends are free to produce a power suction effect on the central part of the chamber for drawing the stream of water through the inlet and then forcibly discharging the same at the

periphery of the chamber by the centrifugal force of the blades, thus insuring a rapid and forcible circulation of the water and keeping the engine in a suitably cooled condition.

Furthermore, this construction of pump is capable of installation on engines now in common use without requiring any alterations or encroaching upon any space now required for other purposes.

Moreover, this pump can be built and installed at comparatively low cost and owing to the small amount of power required for its operation, the efficiency of the automobile is not lowered.

I claim as my invention:

A pump comprising a cylindrical impeller chamber provided at one end with a fixed head, a tubular bracket arranged on said fixed head and having an inner stationary

bearing next to said fixed head and an outer stationary bearing remote from said fixed head, and an outlet at the side of the chamber, said chamber, fixed head, tubular bracket, bearings and outlet being formed integrally, a rotary impeller arranged in said chamber, a shaft extending through said bracket and journaled in said stationary bearings and connected with said impeller, and a separate head detachably connected with the other end of said chamber and having an angular end inlet which extends from said separate head laterally and then lengthwise of the chamber and along the outer side thereof in the same direction in which said bracket extends from said stationary head, said shaft being wholly out of engagement with said detachable head and supported solely by said bearings on the bracket.

CLARENCE W. NEUPERT.
